UNITED STATES PATENT OFFICE.

EDMUND A. HEY, OF CHICAGO, ILLINOIS, ASSIGNOR TO WIREBOUNDS PATENTS COMPANY, OF KITTERY, MAINE, A CORPORATION OF MAINE.

BOX.

1,233,471.

Specification of Letters Patent. Patented July 17, 1917.

Application filed September 25, 1912. Serial No. 722,168.

To all whom it may concern:

Be it known that I, EDMUND A. HEY, a citizen of the United States, and a resident of Chicago, in the county of Cook and State 5 of Illinois, have invented an Improvement in Boxes, of which the following description, in connection with the accompanying drawings, is a specification, like characters on the drawings representing like parts.

10 This invention relates to the art of manufacturing wire bound and other boxes, and more particularly to a case for receiving bottled goods and the like.

Among other objects, the invention provides a case which may be made of light 15 and cheap wood or other material, but which will be sufficiently strong to effectively support the heavy articles carried thereby.

The invention may be best understood by 20 the following description of a method for making the illustrative box disclosed in the accompanying drawing, wherein:

Figure 1 is a plan view of an illustrative box embodying the invention;

25 Fig. 2 is an end elevation of the box shown in Fig. 1;

Fig. 3 is a transverse vertical section taken on line 3—3 of Fig. 1; and

30 Fig. 4 is a transverse vertical section taken on the line 4—4 of Fig. 1.

In accordance with the preferred construction, each side sheet 1, 3 and 5 is shaped and finished individually and is subsequently assembled with previously shaped 35 and finished cleats 7, 9 and 11. The illustrative cleats shown are provided with tongues and grooves at their ends before being assembled with the side sheets.

To reinforce the box and perform other 40 functions more fully hereinafter described, reinforce sheets 15 and 17 may be provided conveniently of the same material and thickness as the side sheets.

The side sheets and reinforce sheets so 45 formed may be readily assembled edge to edge with the reinforce sheets at the ends of the series and be so held by any suitable means.

Binding wires 19, 21, 23 and 25 are then 50 laid upon the opposite sides of the sheets from the cleats. Wires 19 and 21 are in line with the cleats so that the wire binding, sheets and cleats may be secured to-

gether by common fasteners, such for example as staples, which may straddle the 55 wire and be driven through the sheets into the cleats. The ends of the wires are preferably left projecting so that when the box blank is folded into box form the opposite ends of each wire may 60 be twisted together as at 19^a, 21^a so as to complete the continuity of the closure as shown in Fig. 2. Before the wire ends are twisted together brace cleats 27 are introduced between the side sheets, 65 and end plates or pieces 29 may be inserted preferably inside the cleats and bear outwardly against them. The end plates may be secured to the cleats by small staples 31 or other suitable fastening means. 70

The binding wires 23 and 25 referred to are laid along the sides at preferably equally distributed points between the ends of the sides and also along the reinforce sheets. These wires 23 and 25 may be anchored to 75 the sheets and reinforce sheets by staples 32 or other suitable fastening means and may be further anchored to the reinforce sheets by bending the ends 25^a of the wires around the free edges of the reinforce sheets. 80

To provide pockets for receiving bottles or the like, partition means is provided illustrated herein as a series of partitions 33 extending transversely across the box and having slots half their depths receiving narrower partitions 35 extending longitudinally of the box. 85

These partitions are introduced through the top of the box and set into the bottom of the box. Then the reinforce sheets are 90 folded around the top edges of the sides as fulcra down into the box against the inner faces of opposite sides of the box. In the course of this movement the wire securely anchored to the reinforce sheets will 95 be tensioned and drawn tightly to embrace and support the sides and bottom of the box. The ends of the binding wires turned over the edges of the reinforce sheets will then be inclosed between the reinforce sheets 100 and side sheets, thereby further assisting in anchoring the wires. The reinforce sheets may be held in any suitable manner. Staples or other fastening means 37 may be driven through the reinforce sheets into the side 105 sheets.

To brace the reinforce sheets against rocking away from the side sheets, brace strips 39 may be provided interposed between said reinforce sheets at the ends of 5 the box and secured to said ends by staples or other suitable fastening means.

Preferably the lower edges of the reinforce sheets engage the transverse partitions 33 referred to and the brace strips engage 10 the longitudinal partitions 35 referred to. As a result, the partitions are effectively held in position.

Side sheets may be formed of one or more strips of wood and when of a plurality they 15 may have a tongue and groove connection as shown at 43.

The box or case described, while simple in construction and of thin material, presents a strong, distortion-resisting construction. The binding wires passing beneath the 20 bottom of the box intermediate the ends of the latter are effectively held taut by their anchorage to the reinforce sheets and effectively tend to resist any bulging or sagging 25 of the bottom under load. The reinforce sheets stiffen the sides of the box and prevent their bulging or buckling when the box is grasped by its brace cleats 27 as handles for carrying the case from place to place.

30 While the illustrative box shown herein is an open case it will be understood that a top might be provided therefor if desired.

Having described one illustrative box embodying the invention without limiting the 35 same thereto, what I claim as new and desire to secure by Letters Patent is:

1. A wire bound box comprising sides, a bottom and ends, having, in combination, a cleat located approximate each end of each 40 side and the bottom, and secured thereto by staples anchoring the side and bottom to their respective cleats; bracing cleats at each end of the top of the box and interposed between the sides; reinforce layers superposed 45 on said sides, and a binding wire embracing said bottom and sides and extended over the edges of the latter and along said reinforce layers.

2. A wire bound box comprising sides, a 50 bottom and ends, having, in combination, a cleat located approximate each end of each side and the bottom, and secured thereto by staples anchoring the sides and bottom to their respective cleats; a bracing cleat at 55 each end of the top of the box and interposed between the sides, binding wires encircling the box at each end and anchored to the sides, and reinforce layers superposed upon the sides of the box and engaging the 60 ends thereof, and a binding wire extending around said bottom and sides over the edges of the latter and along said reinforce layers.

3. A wire bound box comprising sides, a 65 bottom and ends, having, in combination, reinforce layers superposed upon the sides of

the box, binding wire encircling the box at each end thereof and binding wire extending along said bottom, sides and reinforce layers.

4. A wire bound box comprising sides, a 70 bottom and ends, having, in combination, reinforce means for the interior of the sides of the box, and binding wire extending along said bottom and sides and anchored to said reinforce means.

5. A wire bound box comprising sides, a 75 bottom and ends having, in combination, reinforce means superposed upon the inner faces of the sides of the box and engaging said ends, and binding wire intermediate said ends extending along said bottom and sides and secured to said reinforce means.

6. A wire bound box comprising sides, a bottom and ends, and reinforce means applied to opposite sides of said box and engaging said ends of the box to resist collapsing of the box.

7. A wire bound box comprising sides, a bottom and ends, having, in combination, reinforce layers superposed upon sides of the 90 box and binding wire extending along said bottom, sides and reinforce layers and having ends bent around the lower edges of said reinforce layers.

8. A wire bound box comprising sides, a 95 bottom and ends, having, in combination, reinforce means superposed upon inner faces of the box, and brace strips extending between said means for holding the latter in position.

9. A wire bound box comprising sides, a bottom and ends, having, in combination, reinforce layers for said sides, bracing strips at the ends of the box interposed between said reinforce layers, binding wire encircling the box at each end and binding wire having ends secured to the lower edges of said reinforce layers and extending over the opposite edges of said layers along the sides and bottom of the box.

10. A box comprising sides, a bottom and ends, having, in combination, partition means within the box, and fixed reinforce means superposed on said sides for holding the partition means in position and to brace 115 the box ends.

11. A box comprising sides, a bottom and ends, having, in combination, pocket forming cross partitions within the box, and fixed reinforce means superposed on said sides for maintaining said partitions in position and to brace the box ends.

12. A box comprising sides, a bottom and ends, having, in combination, partition means within the box extending from side 125 to side thereof, reinforce layers superposed upon faces of opposed sides of said box and having lower edges for preventing displacement of said partition means.

13. A box comprising sides, a bottom and 130

- ends, having, in combination, partition means, reinforce layers located closely against opposite sides of the box, and bracing strips interposed between the said reinforce layers, the layers and strips bracing said box completely in all directions. 5
14. A box comprising sides, a bottom and ends, having in combination, partition means, reinforce layers superposed upon opposite sides of the box, and bracing members interposed between said reinforce layers, said layers and members having lower edges for limiting displacement of said partition means. 10
15. 15. A wire bound box comprising sides, a bottom and ends, having, in combination, partition means, reinforce layers superposed upon opposite sides of the box, bracing members for holding said reinforce layers in position, said layers and members being arranged to limit displacement of said partition means, and binding wire having ends engaging the lower edges of said reinforce layers and extending along the latter from the upper edges of the same and along the sides and bottom of the box. 20
16. A wire bound box comprising sides, a bottom and ends, having, in combination, reinforce layers superposed upon said sides, and binding wire having ends bent in between said sides and layers and extending along the latter and the sides and bottom of the box. 30
17. A wire bound box comprising sides, a bottom and ends, having, in combination, reinforce layers superposed upon said sides, a binding wire having ends locked around the lower edges of said layers and between the latter and said sides, said binding wire extending along said layers to the top edges thereof and along the exterior of said sides and bottom, and bracing means interposed between said reinforce layers for holding the same in position. 40
45. 18. A wire bound box comprising sides, a bottom and ends, having, in combination, reinforce layers superposed upon said sides, a binding wire anchored to the lower portions of said layers and extending along the same, over the edges of said layers and sides and along the exterior of said sides and bottom, and staples for anchoring said binding wire to said sides and bottom.
19. A wire bound box comprising sides, a bottom and ends, having, in combination, reinforce layers shorter than said sides and superposed upon the latter; means to secure said layers to said sides; and binding wires having ends anchored to the lower edges of said reinforce layers and extending along the latter over the edges thereof and exteriorly along said sides and bottom. 55
20. A wire bound box comprising sides, a bottom and ends, having, in combination, reinforcing layers superposed upon the sides of said box, and binding wire extending along said sides and bottom over the top edges of said sides and along said reinforce layers; and means to anchor said wire to said reinforce layers. 60
21. An open top wire bound box comprising sides, a bottom and ends, having, in combination, partitions in said box, reinforce layers superposed upon inner faces of opposed sides of said box; bracing strips interposed between said reinforce layers and secured to the ends of the box; cleats anchored to end portions of said sides and bottom; binding wires encircling said box at its ends; staples for anchoring said wires to said sides, bottom and ends, and binding wire intermediate said ends extending exteriorly along said bottom and sides over the top edges of the latter and along said reinforce layers; and staples for anchoring said binding wires to said bottom, sides and layers. 70
22. A box comprising sides, a bottom and ends, having in combination, partition means within the box, fixed reinforcing means superposed on said sides for holding the partition means in position and wires embracing the bottom and sides of the box and secured to said reinforcing means. 80
- In testimony whereof, I have signed my name to this specification, in the presence of two subscribing witnesses. 95
